CLAIM

The ornamental design for a mounting plate for a bill validator kit and reel assembly for a gaming machine, as shown and described.

DESCRIPTION

FIG. 1 is an isometric view of the mounting plate for a bill validator kit and reel assembly for a gaming machine showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left elevational view thereof; and,

FIG. 7 is a right elevational view thereof.
